UNITED STATES PATENT OFFICE.

MILES SWEET, OF TROY, NEW YORK, ASSIGNOR TO SWEET & CLARK MANUFACTURING COMPANY, OF SAME PLACE.

DESIGN FOR A CURRY-COMB BACK-HANDLE.

SPECIFICATION forming part of Design No. 14,108, dated July 17, 1883.

Application filed May 3, 1883. Term of patent 14 years.

To all whom it may concern:

Be it known that I, MILES SWEET, a citizen of the United States, residing at Troy, in the county of Rensselaer and State of New York, 5 have invented and produced a new and original Design for a Curry-Comb Back-Handle or Elevated Grasp, of which the following is a specification, reference being had to the accompanying drawing, forming a part thereof, in 10 which is represented a perspective view of a curry-comb having my newly-designed handle elevated above the back thereof.

Heretofore the serrated plates of curry-combs have been united together at their edges by a 15 rectangular frame, and said frame has been provided with transverse grasping devices of suitable form, elevated above the frame; but I am not aware that any of these elevated grasping devices have been made in the form of a 20 horseshoe, although the frame lying upon the serrated plates and uniting them together has been made in the form of a horseshoe, with the front comb-plates shorter than the other, and the wooden handle in a plane above said 25 frame.

The leading feature of my design consists in the peculiar configuration of the curry-comb back-grasp, being in the form of a horseshoe

of suitable size, elevated upon legs or braces, and located in the same plane with the wooden 30 handle of the curry-comb.

To describe the invention more fully, A represents a series of serrated comb-bars of uniform size, under a frame, B, made with rectangular but slightly-rounded corners and scalloped edges b. At a suitable elevation (of about an inch) above the comb-bars the curry-comb has a back-handle, the general contour of which is in the form of a horseshoe, B', with a horse - hoof frog, B'', in the center thereof, 40 legs or braces B', connected with the frame B, and a tang, B', in the same horizontal plane with the horseshoe-handle, and in line with said tang the handle C, of usual form, is located; and by these characteristics the design is easily 45 recognized.

I claim—

The design for a curry-comb elevated back-grasp herein shown and described, the same consisting of a handle having the contour of a 50 horseshoe, B', with legs or braces B' between it and the frame B.

MILES SWEET.
